DESIGN FOR A LACE

Isaac Zendman, Jr., New York, N. Y.

Application February 26, 1942, Serial No. 105,995

Term of patent 3½ years

To all whom it may concern:

Be it known that I, Isaac Zendman, Jr., a citizen of the United States of America, residing in New York city, county of New York, and State of New York, have invented a new, original, and ornamental Design for a Lace, of which the following is a specification, reference being had to the accompanying drawing, forming part thereof, wherein the figure of the drawing is a plan view of a lace showing my new design.

I claim:

The ornamental design for a lace, substantially as shown.
